UNITED STATES PATENT OFFICE.

EDMOND W. T. RICHMOND, OF ROMFORD, ENGLAND.

DESIGN FOR A GAS-STOVE.

SPECIFICATION forming part of Design No. 33,883, dated January 8, 1901.

Application filed December 11, 1900. Serial No. 39,563. Term of patent 7 years.

To all whom it may concern:

Be it known that I, EDMOND WALTER TYRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design are the filigree grate A, the upper front portion C, having the central escutcheon D, on opposite sides of which there are dragon-heads E and below which there are scrolls F, the side portions G ornamented by a vertical series of fan-shaped figures and the front portion, be-

low the grate, ornamented by the quatrefoil figures H, between which are arranged the 20 dentils h.

The top of the stove has its edge projecting beyond the body portion, and this edge is ornamented, and centrally on the top of the stove there is a series of upwardly-projecting 25 ribs I.

I claim—

The design for a gas-stove, substantially as herein shown and described.

In testimony whereof I have hereunto sub- 30 scribed my name.

EDMOND W. T. RICHMOND.

Witnesses:

KATHARINE MACMAHON,
EDWARD C. DAVIDSON.
